DESIGN FOR A COAT

Jules Freedman, New York, N. Y., assignor to
Morris W. Haft & Bros., Inc., New York, N. Y.

Application November 12, 1948, Serial No. 149,599

Term of patent 3½ years

(Cl. D3—4)

To all whom it may concern:

Be it known that I, Jules Freedman, a citizen of the United States of America, residing in New York city, county of Kings, and State of New York, have invented a new, original, and ornamental Design for a Coat, of which the following is a specification, reference being had to the accompanying drawing, forming part thereof, wherein,

Figure 1 is a front elevational view of a coat, showing my new design.

Figure 2 is a rear elevational view of the coat shown in Figure 1.

I claim:

The ornamental design for a coat, substantially as shown.

JULES FREEDMAN.
